**METHOD FOR EDGE CRIMPING THERMO-
PLASTIC YARNS**

William P. Warthen, Spartanburg, S.C., assignor to Deering Milliken Research Corporation, Spartanburg, S.C., a corporation of Delaware

Filed Oct. 10, 1962, Ser. No. 229,563
10 Claims. (Cl. 28—72)

This invention relates to a process for crimping thermoplastic filaments and to apparatus for carrying out the process.

Continuous filament thermoplastic yarns are commonly crimped by a process known as "edge crimping." In an "edge crimping" process, a thermoplastic yarn heated to an elevated temperature is drawn over a sharply angular body or deforming edge whereby the yarn is stressed in a manner such that the filament or filaments comprising the yarn assume a highly convoluted configuration. This method of crimping continuous filament thermoplastic yarns is highly desirable for the reason that yarns crimped by this method normally have little or no tendency to twist and can readily be employed single ply. Edge crimping also differs from most other methods of crimping thermoplastic yarns in that the elastic nature of a yarn processed in this manner is only partially apparent following passage of the yarn about the deforming edge, and a heat treatment is necessary to develop its full elastic nature.

Edge crimped yarn crimping apparatus have employed various edges for effecting the crimp. The crimping edges have been edges such as stationary edges, reciprocating edges and rotating edges such as that provided by the inner surface of a rotating ring or tube. A fairly recent innovation, however, in the field of edge crimping apparatus is the use of a traveling length of the filament itself as a crimping member. When a filament crimping member is employed, the filament to be crimped is passed in a heated condition and under tension over and in contact with a portion of the same filament traveling across the path of the filament to be crimped so that the latter filament is sent over the aforesaid traveling filament at an angle thereby becoming potentially crimpable.

Certain problems have developed, however, in the use of a filament as the crimping member for a continuous thermoplastic filament. Some of the problems experienced in using a filament medium are riding, binding and breaking of the filament to be crimped on the filament crimping member. The term "riding" as used herein is meant to define a traversing movement of the filament to be crimped on the filament crimping member and more specifically a traversing movement of the filament to be crimped in the direction of movement of the filament crimping member. Another common problem is failure of the filament to be crimped to receive sufficient contact with the filament crimping member as to impart sufficient crimps per inch necessary for a commercial product.

It is therefore an object of this invention to provide a method for crimping thermoplastic continuous filaments in a system employing a traveling filament as a crimping member in a manner such that the crimped filament has that number of crimps per inch which renders the filament a commercial product.

2

It is another object of this invention to provide a method for crimping a continuous thermoplastic filament in a system employing a moving filament as a crimping member in a manner such that the thermoplastic continuous filament to receive the crimp does not ride, bind or break on the filament crimping member.

It is still another object of this invention to provide apparatus of the type employing a moving filament as a crimping member for crimping continuous thermoplastic filaments, the apparatus being designed so as to prevent the filaments to be crimped from riding, binding or breaking and also designed so as to allow the filament to be crimped to have sufficient contact with the running filament crimping member as to give the filament to be crimped a full degree of crimp.

In accordance with this invention, it has now been discovered that a running length of thermoplastic filament may be crimped in an improved manner by softening said yarn under the influence of heat and immediately wrapping said yarn around a single length of itself, the wrap covering not less than a 360° turn. It should be understood that the crimping operation may be carried out once or a plurality of times, that is to say, the running length of yarn may be softened under the influence of heat and immediately wrapped about a plurality of separate lengths of itself, each wrap covering not less than a 360° turn about a single length. The improved crimp is also effected by means of a process and apparatus which prevent riding, binding and breaking of the filament. Riding, binding and breaking of the filament are prevented by progressively passing said filament through an angle about a small radius generally convexly curved surface formed by a preceding linearly progressed segment of said filament moving transversely across the direction of movement of the portion of said filament passing through said angle, said preceding linearly progressed segment of said filament assuming a V-shaped path and said filament to be crimped being bent through an angle of at least 360° over said linearly progressed segment. The V-shaped path of the filament crimping member is an inherent feature of a process wherein the filament to be crimped is under less tension than the preceding linearly progressed segment. The V-shaped path of the filament crimping member is maintained without the filament to be crimped riding or binding and thereby destroying the V-shaped configuration by passing that linearly progressed segment forming the filament crimping edge through entrance and exit spaced-apart yarn guides disposed on opposite sides of the apex of said V-shaped path, said exit yarn guide being spaced upstream from said entrance yarn guide with respect to the direction of flow of the yarn to be crimped.

The apparatus and process of this invention have solved the problem of poor crimping which was a detrimental feature in heretofore known processes for crimping a yarn by employing a continuous moving yarn as a crimping member. In order to set forth the improvement of this invention, it is necessary to define the term "crimping." A thermoplastic monofilament treated by means of an edge crimping process will assume a helical configuration. A helical configuration may be measured in terms of amplitude and frequency. When an edge crimped yarn is under substantially no tension, frequency measure-

ments may be ignored and crimp measurements for the monofilament may be based on amplitude alone. Amplitude determination of edge crimped monofilament yarns is made by cutting the crimped monofilament into short lengths and placing the short lengths on a gridded screen calibrated in millimeters. Each of these short lengths is found to produce a coil of more or less circular size. The diameter of the coils may then be measured by means of the gridded screen. Useful coil size or crimp size is usually considered to be in the range of 0.4 mm. to 1.0 mm. In a process employing a segment of yarn as a deforming edge, the desired coil size range may only be obtained by contacting the yarn to be crimped with the yarn deforming edge for at least one full turn or 360°. It has also been found that in order to obtain the desired coil size range that the speed of the yarn receiving a crimp should preferably be no greater than 40 yards per minute. Where the rate of yarn travel is in excess of 40 yards per minute, it is beneficial to combine a cooling device with the crimping apparatus of this invention. The cooling device which may be a device such as, for instance, a heat sink of a metal having high thermal conductivity, an air jet, a water pad or the like, should be placed immediately behind the yarn crimping edge so as to cool the crimped yarn as soon as possible thereby preventing tension on the crimped yarn from removing the newly formed crimp.

The filament to be crimped according to the method set forth in this invention should be a thermoplastic filament and preferably a thermoplastic monofilament. The denier size may be from 15 denier to 180 denier. Specific thermoplastic polymers which are suitable for use in this invention are polymers such as, for instance, polyhexamethylene sebacamide, polyhexamethylene adipamide, polycaprolactum and the like. The thermoplastic polymers employed in this invention should be heated prior to being subjected to the crimping medium to temperatures of from greater than 180° F. to a point at least 80° F. below the melting point of the specific thermoplastic polymer being employed. Tensions applied to the thermoplastic materials in this invention, during and subsequent to the crimping operation, will vary according to the specific thermoplastic materials and specific temperatures employed. Tensions applied to a 15 denier nylon monofilament for instance, at the point of wrap about the crimping segment, are from 0.5 gram to 3.5 grams at a temperature range of from 180° F. to 450° F. The tensions, subsequent to crimping operations, must not be great enough to remove substantial amounts of useful crimp applied to the yarn.

A better understanding of the invention may be had from a discussion of the drawings which are as follows:

FIGURE 1 is a diagrammatic view of one type of yarn crimping apparatus of this invention.

FIGURES 2 and 3 are expanded fragmentary views of a portion of the apparatus shown in FIGURE 1.

FIGURES 4 and 5 are further arrangements for accomplishing the purposes of this invention.

FIGURE 6 is a diagrammatic view of another type of yarn crimping apparatus of this invention.

FIGURE 7 is an expanded fragmentary view of a portion of the apparatus shown in FIGURE 6.

In FIGURE 1, yarn is fed from a supply bobbin 1 through a tensioning device 2 onto yarn advancing means 3 and 4. The yarn advancing means are actuated by a suitable driving means, all of the yarn advancing means of the apparatus being synchronized by the driving means. Yarn advancing means 3 has a small diameter section 5 and a large diameter section 6. Yarn advancing means 4 has a small diameter section 7 and a large diameter section 8. The small and large diameter sections of both yarn advancing means 3 and 4 rotate in unison. Yarn passing from tensioning device 2 is passed about the small diameter sections 5 and 7 of yarn advancing means 3 and 4, respectively, a plurality of times. The yarn

is then passed over guide rolls 9 through entrance guide 10 and exit guide 11 to form the crimping section 12. The yarn is then passed over large diameter sections 6 and 8 of yarn advancing means 3 and 4, respectively, a plurality of times and then over hot roll 13. The crimping member is maintained under the desired tension by selecting the proper ratio of surface speeds between small roll section 5 and large roll section 6 of yarn advancing means 3. The surface speed of the large roll section 6 should be 1.5% to 4% faster than the surface speed of small roll section 5. Hot roll 13 may be heated by any convenient means such as, for instance, electricity, liquid organic heat transfer mediums and the like. The surface speed of hot roll 13 is approximately equal to or slightly in excess of that of large roll section 6 of yarn advancing means 3. Yarn passing from hot roll 13 is then wrapped about crimping segment 12 through a wrap of at least one full turn or 360°. The yarn coming off hot roll 13 and being wrapped about crimping segment 12 is under less tension than crimping segment 12 in that the yarn coming from hot roll 13 has been overfed with respect to cold roll 14 which has a surface speed approximately equal to or slightly less than that of hot roll 13, and overfed with respect to yarn advancing means 15 and 16, yarn advancing means 15 having a surface speed of from 15% to 35% less than the surface speed of sections 6 and 8 of advancing rolls 3 and 4. A better understanding of the crimping operation which takes place in wrapping the heated yarn about the crimping segment 12 may be had from FIGURES 2 and 3 of the drawings. FIGURE 2 clearly illustrates the V-shaped configuration of the crimping segment 12 which has been formed by passage of yarn about guide roll 9 through entrance guide 10 and exit guide 11. The yarn to be crimped which passes from hot roll 13, which is shown in phantom view, is wrapped in excess of 360° about crimping segment 12 before being passed over cold roll 14. The staggered positioning of entrance yarn guide 10 and exit yarn guide 11 may be seen in FIGURE 3. In FIGURE 3, crimping segment 12 is formed by passage of yarn between entrance yarn guide 10 and exit yarn guide 11. Exit yarn guide 11 is positioned upstream from entrance yarn guide 10 with respect to the direction of flow of the yarn to be crimped which is illustrated as passing over crimping segment 12 in a wrap of at least 360°. Returning to FIGURE 1, the yarn coming off crimping segment 12 is then passed over cold roll 14 and then about yarn advancing rolls 15 and 16 a plurality of warps. The surface speed of yarn advancing rolls 15 and 16 is less than the surface speed of hot roll 13 and cold roll 14. The reduced surface speed of yarn advancing rolls 15 and 16 reduce the tension on the newly crimped yarn and thereby insure retention of maximum amounts of crimp. The yarn passing from yarn advancing rolls 15 and 16 is then wound on take-up package 17.

It should be understood that the yarn to be crimped may be wrapped about the crimping segment for more than one full wrap and also may be wrapped about a plurality of crimping segments, each wrap covering not less than a 360° turn. The aforementioned features are clearly illustrated in FIGURES 4 and 5, respectively. In FIGURE 4 a crimping segment 22 is formed by passage of yarn between entrance yarn guide 20 and exit yarn guide 21. The yarn to be crimped is then passed about crimping segment 22 for a plurality of wraps. Apparatus employing a plurality of crimping segments is illustrated in FIGURE 5. Yarn is passed between entrance yarn guides 30 and exit yarn guides 31 to form crimping segments 32. Yarn leaving exit yarn guides 31 is turned about guide rolls 33 so as to be in position for the formation of additional crimping segments 32. The yarn to be crimped is then wrapped about each separate crimping segment 32 for a wrap of not less than 360°.

To facilitate ease of threading the apparatus at the start of crimping operations, another form of apparatus may be employed which is illustrated in FIGURE 6. In FIGURE 6 yarn is passed from supply bobbin 41 to yarn advancing means 42 and 43. The yarn advancing means are actuated by a suitable driving means, all of the yarn advancing means of the apparatus being synchronized by the driving means. Yarn advancing means 42 is divided into three sections which are an intermediate diameter section 44, a large diameter section 45 and a small diameter section 46. Yarn advancing means 43 is also divided into three sections which are an intermediate diameter section 47, a large diameter section 48 and a small diameter section 49. Both yarn advancing means 42 and 43 are unitary devices, that is to say, the three sections composing each of the two rolls rotate in unison. The devices 42 and 43 are also driven in such manner that their three respective sections have the same surface speed. Yarn from supply package 41 is wrapped about intermediate diameter sections 44 and 47 of yarn advancing means 42 and 43, respectively for a plurality of wraps and is then brought about roller guide members 50 through entrance guide 51 and exit yarn guide 52 to form crimping segment 53. The crimping segment 53 is shown in raised position, the raised position being obtained by the ability of roller guides 50 to function as hinges thereby providing a swinging arm member. When crimping segment 53 is in use, it is lowered into the position shown in the phantom view. After formation of crimping member 53, the yarn is returned over roller guides 50 to large roll sections 45 and 48 of yarn advancing means 42 and 43, respectively. The yarn is wrapped a plurality of times about large diameter sections 45 and 48 and then passed over hot roll 54. The surface speed of the large diameter section 45 should be 1.5 to 4% faster than the surface speed of intermediate diameter section 44. Hot roll 54 may be heated by any convenient means such as, for instance, electricity, organic heat transfer mediums and the like. The surface speed of hot roll 54 is approximately equal to or slightly in excess of that of large roll section 45. After passage over hot roll 54, the yarn is wrapped about crimping member 53 through a wrap of at least 360°. A better understanding of the crimping operation which takes place at this point may be had from a discussion of the expanded fragmentary view of the crimping edge portion of the apparatus shown in FIGURE 7. In FIGURE 7 yarn is passed over entrance yarn guide 51 to exit yarn guide 52 to form crimping segment 53. Yarn guides 51 and 52 are adjustably carried by arm member 58. Exit yarn guide 52 is positioned upstream from entrance yarn guide 51 with respect to the direction of flow of the yarn to be crimped. The yarn to be crimped is wrapped about crimping segment 53 for at least one full turn or 360°. The staggered relationship of exit yarn guide 52 to entrance yarn guide 51 prevents the filament to be crimped from riding up the crimping segment 53 to a position adjacent exit yarn guide 52. Returning to FIGURE 6, crimping segment 53 retains its proper V-shaped configuration by reason of the fact that it is under greater tension than the yarn to be crimped.

The yarn coming off hot roll 54 and being wrapped about crimping segment 53 is under less tension than crimping section 53 in that the yarn forming crimping section 53 has been overfed with respect to large roll section 45 of yarn advancing means 42 by an amount to obtain the desired tension. The yarn coming off hot roll 54 and being wrapped about crimping segment 53 is under less tension than crimping segment 53 in that the yarn coming from hot roll 54 has been sufficiently overfed with respect to cold roll 55 and oil roll 56, each of which have a surface speed approximately equal to or slightly less than that of hot roll 54, and sufficiently overfed with respect to small diameter sections 46 and 49 of yarn

advancing means 42 and 43, respectively, small diameter sections 46 and 49 having surface speeds of from 15% to 35% less than the surface speed of large roll sections 45 and 48 of yarn advancing means 42 and 43, respectively. Passage of the yarn about small diameter sections of yarn advancing means 42 and 43 decreases the tension on the crimped yarn and thereby diminishes the possibility of removing the newly set crimp from the yarn. The yarn is then taken off yarn advancing means 42 and 43 and wound on take-up package 57.

The apparatus and process of this invention have solved the riding, binding and breaking problem and the problem of formation of useful crimp size in the yarn by passage about the yarn itself. The riding of the yarn to be crimped has been solved by two novel improvements, the first of which is the positioning of the guides which properly position the crimping segment and the second of which is the regulation of the crimping segment under a greater tension than that of the yarn to be crimped. The maintenance of crimping segment tension at higher values than that of the yarn to be crimped is obtained by proper regulation of the surface speeds of the yarn advancing means. The surface speeds of the yarn advancing means have been discussed in conjunction with the explanation of FIGURES 1 and 6. The formation of useful crimp size in the crimping of yarn by passage about the yarn itself is obtained by passage of the yarn about itself in a wrap of not less than 360°.

What is claimed is:

1. The method of edge crimping a running length of thermoplastic yarn comprising softening said yarn under the influence of heat and immediately wrapping said yarn about a single length of itself, the wrap covering not less than a 360° turn.

2. The method of edge crimping a running length of thermoplastic yarn comprising softening said yarn under the influence of heat, immediately wrapping said yarn around a single length of itself, the wrap covering not less than a 360° turn and then drawing said running length of yarn out of the wrapped configuration and cooling.

3. The method of edge crimping a running length of thermoplastic yarn comprising softening said yarn under the influence of heat, immediately wrapping, a wrap covering not less than a 360° turn, said softened yarn sequentially about a plurality of single lengths of itself and then drawing said running length of yarn out of the wrapped configuration and cooling.

4. In a yarn edge crimping process wherein a running length of thermoplastic filament to be crimped is heat softened and progressively passed through a turn of at least 360° by wrapping said filament about a convexly curved surface formed by a preceding linearly progressed segment of said filament passing transversely across the direction of movement of the filament proceeding through the turn, the improvement comprising maintaining said running length of filament to be crimped at a lesser tension than said preceding linearly progressed segment.

5. A yarn crimping process according to claim 4 wherein in the filament which is passing transversely across the direction of movement of the portion of said filament being crimped, and the filament to be crimped, are linearly progressed at a rate no greater than about 40 yards per minute.

6. A yarn crimping process according to claim 4 wherein in the thermoplastic filament to be crimped has a denier size ranging from about 15 to about 180.

7. A yarn crimping process according to claim 6 wherein in the thermoplastic filament is heated to temperatures of greater than about 180° F. to a point at least 80° F. below the melting point of the specific thermoplastic polymer constituting the filament.

8. A yarn crimping process according to claim 7 wherein the thermoplastic filament is nylon.

9. A yarn crimping process according to claim 8 wherein tensions maintained upon the filament range from about 0.5 gram to about 3.5 grams and the temperature ranges from about 180° F. to about 450° F.

10. A yarn crimping process according to claim 4 wherein a heat softened thermoplastic filament to be crimped is progressively wrapped about a plurality of individual and single lengths of preceding linearly progressed segments of said filament passing transversely across the direction of movement of the portion of said

5
10

filament being crimped, each wrap about the individual filament constituting not less than one full turn.
